7 Claims. (Cl. 242—75.53)

Our invention relates to devices for regulating the winding tension in tape, sheet or other web material as it travels onto a core or beam onto which it is being wound.

Our invention more particularly relates to a device for regulating the winding tension of web material, for example sheets of paper, arrays of textile threads such as warp threads and the like, which passes in front of the winding beam through a pull-off or pinch roller device having a pinch roller that is pivotally mounted and serves for controlling the winding speed in dependence upon its pivotal displacements. Such regulation has been performed heretofore with the aid of a roller that engages the travelling web material ahead of the winding beam and varies its position in dependence upon the winding tension, the resulting displacement of the roller being used for controlling the winding speed as needed to maintain the tension within desired limits. A sensing roller of this kind is generally known as a "dancer roll." Its tension-responsive displacement may be predominantly in the vertical or horizontal direction. It has also been known to pivotally mount one of the pull-off or pinch rollers ahead of the winding beam and to utilize the tension-responsive pivotal displacements of this roller for controlling the winding speed. In this known device, the pivotally displaceable roller has its pivot axis coincident with the rotational axis of the adjacent pull-off roller so that the displacing motion is on a path concentric to the other pull-off roller and the displaceable roller is capable of performing a rolling movement on the cylindrical surface of the other pull-off roller. This device, however, has a disadvantage in that the angle with which the material runs onto the winding beam is varied not only by the increasing diameter of the winding being produced but also by the additional pivoting motion of the tension-responsive roller.

It is therefore an object of our invention to achieve a performance in which the material being wound will always run onto the winding beam at almost the same angle for a given diameter of the winding, regardless of the position which the pivotally mounted roller of the pull-off device may occupy at the time.

Another object of our invention is to provide a tension-regulating device for web winding operations which is capable of maintaining an approximately constant tension in the web material in the entire diametrical range of the winding operation.

Still another object of our invention is the provision of a device for regulating the winding tension in web material which simultaneously acts as a clamping device to prevent the material from being pulled out of its position when the material is being cut off at the winding beam, for example upon completion of a winding.

To achieve these and such further objects as will appear from the following, and in accordance with a feature of our invention, we mount the pivotally displaceable roller of a pull-off device in a beaming or winding machine for material of the above-mentioned general kind so as to have its pivot axis located in spaced relation to the rotational axis of the adjacent pull-off roller.

The foregoing and other objects, advantages and features of our invention, said features being set forth with particularity in the claims annexed hereto, will be apparent from, and will be mentioned in, the following with reference to an embodiment of a tension regulating device on winding equipment as used for example in a sizing machine, illustrated by way of example on the accompanying drawings in which:

FIG. 1 is a front view partly in section through the essential components of the machinery; and

FIG. 2 is a sectional view along the line II—II in FIG. 1 in the direction of the arrows.

Shown at F in FIG. 1 is an array of warp threads coming from supply spools usually mounted on a creel and which are to be wound upon a warp beam 1. Mounted ahead of the beam 1 relative to the travelling direction of the material is a pull-off roller device which comprises three pinch rollers 2, 3 and 4. The roller 3 rotates about a fixed axis 3a. The rotational axes 2a and 4a of the respective rollers 2 and 4 are not fixed but can perform pivotal movements in the illustration plane of FIG. 1. In the illustrated embodiment, the shaft of roller 4 has its bearings mounted in an arm 4c pivotally fastened to a disc 5 which is rotationally journaled about an axis 5a in eccentric relation to the rotational axis 3a of the roller 3. The eccentric disc 5 is connected by a chain 6 with a sprocket wheel 8 fixed to a torsionally rigid shaft 7. Also mounted on shaft 7 in fixed relation thereto is a spur gear 9 which meshes with a rack 10 linked to a piston 11. The piston 11 is displaceable in a hydraulic cylinder 12 whose internal pressure is indicated by a measuring instrument 13 and adjustable with the aid of a pressure-limit valve 14. The stiff shaft 7 is connected through a chain transmission 15 with a control valve 16 which serves for changing the angular speed of the winding beam 1 by conventional means shown diagrammatically in FIG. 1. Since hydraulically controlled drives for beaming machines are well known and their particular design is not essential to the invention, these drive means are not further illustrated or described in this specification.

During the winding operation, the length of the warp F between the pull-off device and the winding beam 1 becomes gradually shorter on account of the increasing diameter of the material wound upon the beam if the angular speed of beam rotation is kept constant. This shortening forces the axis of the roller 4 to pivot clockwise (FIG. 1) about the pivot axis 5a. The eccentric disc 5 turns together with the pivotal displacement of the roller 4 and hence also in the clockwise sense. The rotation of the eccentric disc 5 is transmitted by the chain 6 to the shaft 7. The revolving motion of shaft 7 is further transmitted through the chain transmission 15 to the valve 16 and thus causes the winding speed of the beam 1 to change toward a lower value. This has the result that the warp material resumes its original length and the roller 4 returns to its original position. In this manner the illustrated device regulates the tension in the warp material during the winding operation to a substantially constant value.

When the material being wound upon the beam, in the present example the array of warp threads 5, is intentionally loosened excessively from the winding beam 1 or is severed for example at the locality T (FIG. 1) then the tension in the upper portion of the warp material breaks down or the material becomes greatly lengthened between the pull-off device and the beam. The pressure in cylinder 12 causes the piston 11 to be displaced toward the left into the position 11 shown in FIG. 1 by dot-and-dash lines. This moves the rack 10 into the dot-and-dash position 10. Simultaneously the spur gear 9 is rotated and turns the shaft 7 with the sprocket 8, thus placing the chain 6 to the dot-and-dash position 6. The eccentric

disc 5 therefore is turned counterclockwise and thereby also pivots the roller 4 to the dot-and-dash position 4 in which the spacing a between the rollers 3 and 4 is varied down to zero. In this position, the roller 4 is firmly pressed against the adjacent roller 3 and thus clamps the warp material so that it cannot become pulled out between the roller pair 2, 3.

It will be understood that in FIG. 2 the roller 4 and the shaft 7 are shown partly broken away in order to prevent obscuring each other. The chain 6 may be provided on only one side or on both sides of the roller 3. The parts 9, 10 and 12 are located laterally of the travel path of the material being wound so as not to interfere with the travel.

As is apparent from FIG. 1, the roller 4 is braced against the eccentric disc 5 through a force storing member which permits adjusting the pressure exerted against the adjacent roller 3 in the dot-and-dash position 4. For this purpose, the roller, being mounted by means of arm 4c for pivoting motion about the axis 4b on eccentric disc 5, carries a pin 18 loaded by a spring 17, the pin resting against the eccentric disc 5. A set screw 19 permits varying the spring pressure. When the warp material is loosened or is cut off at the locality T so that the roller 4 reaches the dot-and-dash position 4 and is placed against the roller 3, the force of spring 17 controls the pressure then existing between the roller in the dot-and-dash position 4 and the roller 3. The angle α_1 defined by the pivot radius of the rotational axis for roller 4 in the dot-and-dash position 4, on the one hand, and by the connecting line from the rotational center 5a of the eccentric 5 and the pivot axis of the roller is smaller than the corresponding angle α existing when the roller 4 is in normal operating position.

To avoid the necessity of accounting for the masses of the roller 4 and its journaling means when adjusting the pressure control valve 14, the roller 4 is given a balanced mounting. To this end, the torsionally stiff shaft 7 carries an arm 20 in form of a cam disc. At point 21 of the cam a chain 22 is fastened, and a compensating weight 23 is suspended from the chain to act as a counterpoise, thus providing for a "mass-free" journaling of the pivotally mounted roller 4.

To those skilled in the art it will be obvious upon a study of this disclosure that with respect to structural and other details as well as regards the particular winding material, the invention permits of various modifications and hence can be given embodiments other than illustrated and described herein, without departing from the essential features of our invention and within the scope of the claims annexed hereto.

We claim:

1. With a beaming machine having a winder beam and at least two coactive pinch rollers mounted ahead of said beam for engaging the beaming material between each other to pull it toward said beam, the combination of a device for regulating the winding tension of the material comprising means for controlling the winding speed of said beam, and comprising said two pinch rollers, one of said rollers having a fixed axis of rotation, mounting structure on which said other roller is journalled, said mounting structure being pivotally rotatable and having a pivot axis spaced from said fixed axis in parallel relation thereto, and transmission means connecting said structure with said winding-speed control device for actuating the latter in accordance with pivotal displacements of said other roller.

2. With a beaming machine having a winder beam and at least two coactive pinch rollers mounted ahead of said beam for engaging the beaming material between each other to pull it toward said beam, the combination of a device for regulating the winding tension of the material comprising means for controlling the winding speed of said beam, and comprising said two pinch rollers, one of said rollers having a fixed axis of rotation, said other roller being located between said fixed-axis roller and said beam relative to the travel of the beaming material, mounting structure on which said other roller is journalled for rotation about an axis parallel to said fixed axis, said mounting structure together with said other roller being pivotally displaceable and having a pivot axis spaced from said fixed axis in parallel relation thereto and closer to said beam than said fixed axis so that shortening and lengthening of the material between said beam and said other roller causes said other roller to be pivotally displaced and to be forced less and more respectively against said one roller, and transmission means between said structure and said speed control device for actuating the latter in accordance with pivotal displacements of said other roller.

3. In a device for regulating the winding tension of beaming material according to claim 1, said mounting structure comprising a member rotatably mounted axially beside said one roller in eccentric relation to said fixed axis, and support means on said member for journalling said other roller.

4. In a device for regulating the winding tension of beaming material according to claim 3, said support means having bearing means for journalling said other roller and being pivotally connected with said eccentric member, and force storing means between said support means and said eccentric member for bracing said other roller against said eccentric member.

5. In a device for regulating the winding tension of beaming material according to claim 1, said mounting structure comprising a member rotatably mounted axially beside said one roller in eccentric relation to said fixed axis, an arm pivotally joined with said eccentric member and having bearing means in which said other roller is journalled, an adjustable spring abutment secured to said arm and elastically engageable with said eccentric member.

6. A device for regulating the winding tension of beaming material according to claim 4, comprising mass equalizing means for substantially compensating the mass of said other roller and support means relative to said force storing means.

7. In a device for regulating the winding tension of beaming material according to claim 6, said mass equalizing means comprising a rotatable cam in driven connection with said transmission means to rotate simultaneously with pivotal displacement of said other roller, a counterpoise, and a suspension member suspending said counterpoise from said cam and extending along the cam contour of said cam.
